TAPING DEVICE

Charles A. Rasanen, Aberdeen, Wash.

Application March 6, 1939, Serial No. 260,139

5 Claims. (Cl. 216—20)

The present invention relates generally to improvements in taping devices and has particular reference to a portable hand taping device for printers' use in taping together a series of matrices, which operation has heretofore been accomplished by hand.

The principal object of the invention is to provide a portable hand taping device which includes means for holding and dispensing a roll of tape, means for moistening the same, and means for applying the moistened tape on the matrix margins or to any other objects to which it is desired to apply a tape of this character.

Another object of the invention is to provide a portable hand taping device of the character designated that is most suitable for newspaper work and especially in the assembly of matrices which are later to be molded into the final sections of a newspaper.

A further object of the invention is to provide a handy portable device of the character set forth that embodies means for holding and feeding a roll of adhesive tape, means for guiding the tape as it is dispensed from the roll, means for tensioning the tape as it is dispensed from said roll, and flexible means for engaging the moistened tape and depressing the same to cause the adherence of said tape to uneven surfaces.

Other objects and advantages will be apparent during the course of the following description.

In the accompanying drawing forming a part of this specification and in which like numerals are employed to designate like parts throughout the same,

Fig. 1 is a side elevation of the improved taping device, showing the supporting frame for the tape reel, the handle, the moistening mechanism, and the flexible applicator mechanism adapted to apply the moistened tape to matrices or other objects to be joined together edge to edge;

Fig. 2 is a plan view of the moistening mechanism, the tensioning mechanism, and the applicator mechanism of the device; and

Fig. 3 is a perspective detailed view, further illustrating the adjustable tape tensioning and the retaining mechanism of the device.

In the newspaper art it has generally been the practice to apply tape to the stereotype mats or matrices by hand, which operation at best is a slow, tedious, and very unsatisfactory method of making up forms in this work in that the tape cannot, as a general rule, be applied in an even and satisfactory manner to the forms, except with the utmost care.

Therefore, I have produced a handy portable

device which includes, broadly, a frame A, a tape dispensing reel B, a moistening roller C, and an applicator D.

The frame A comprises a handle 5 which may be grasped by the operator in actual operation. The handle 5 also includes an integrally formed extension 6, at the outer end of which the applicator D, comprising a brush 7, is positioned. The frame A is provided with a pivot bolt 8 and a nut 9, and the tape reel B is mounted on this bolt 10 and may be changed from time to time as occasion requires.

Secured to the frame A, as disclosed in Fig. 1, is a fixed arm 10 having pivoted at its outer end a gravity actuated guard 11 having flanged sections 12 capable of guiding the tape from the reel and also including a weighted end 13 adapted to engage the tape to prevent too rapid unreeling of the same by placing frictional contact on the reel.

The device also embodies a reservoir 14 attached to the extension 6 in any suitable manner, as by screws 15, and the moistening roller 16 is pivotally mounted in this reservoir at 17 and contacts the tape in the manner hereinafter set forth.

Arranged adjacent to and cooperating with the moistening roller 16 is a friction controlled element 18 pivoted to the frame at the point 19 and including a roller sleeve 20 and capable of being raised to the dotted position shown in Fig. 1. This element 18 places tension on the tape 21 ordinarily, but when raised from the contacting tape releases the same from the moistening roller 16 when the device is inoperative.

Referring now to Fig. 3, it will be observed that the element 18 is U-shaped in configuration and normally rests over the tape 21 and which when manually raised by means of an extension 22 allows the tape to be raised from the roller 16 when the device is out of use.

The roller 16 may be provided with flanges 23 to retain the tape 21 thereon, and the reservoir 14 may be supplied with a filling funnel element 24, as shown in Fig. 2.

It is apparent that when the tape is fed from the reel and is led under the roller 20, over one section of the element 18, over the moistening roller 16, and under the applicator brush 7, said tape will be properly moistened and depressed by the brush element to cause said tape to engage and adhere to all uneven surfaces of any structures to which the device may be applied.

It is to be understood that the form of my invention herewith shown and described is to be

taken as a preferred example of the same and that various changes relative to the material, size, shape and arrangement of parts may be resorted to without departing from the spirit of 5 the invention or the scope of the subjoined claims.

Having thus described my invention, I claim:

1. In a device of the class described, a supporting frame, a tape dispensing reel mounted upon 10 said frame, a tape on said reel moistening means mounted upon said frame and capable of contacting said tape, an applicator mounted on said frame adjacent to said moistening means and capable of depressing and adhering the moistened tape to surfaces of uneven character, and a tension member associated with the moistening means, said tension member being pivoted on the frame and U-shaped forming two parallel arms, 15 the tape passing over one arm and under the other arm and capable of being swung away 20 from said moistening means.
2. A hand taping device, comprising a handle, a tape dispensing reel mounted thereon, an extension carried by the handle, an application brush carried by the outer end of said extension, 25 a tank carried by the lower face of the extension adjacent the brush, a moistening roller mounted in the tank and extending above the upper end thereof, whereby a roll of tape may be mounted on the reel and passed over the moistening roller and under the brush.
3. A hand taping device comprising a handle, a tape dispensing reel mounted thereon, an extension carried by the handle, an application brush carried by the outer end of said extension, 30 a tank carried by the lower face of the extension adjacent the brush, a moistening roller mounted 35

in the tank and extending above the upper end thereof, a tension device above said moistening roller, whereby a roll of tape may be mounted on said reel and passed between the tension device and moistening roller and under the application brush. 5

4. A hand taping device, comprising a handle, a tape dispensing reel mounted thereon, an extension carried by the handle, an application brush carried by the outer end of said extension, 10 a tank carried by the lower face of the extension adjacent the brush, a moistening roller mounted in the tank and extending above the upper end thereof, a tension device above said moistening roller and comprising two spaced arms, 15 whereby a roll of tape may be mounted on the reel and passed over one arm and over the moistening roller and under the other arm of the tensioning device and under the application brush.

5. A hand taping device, comprising a handle, 20 a tape dispensing reel mounted thereon, an extension carried by the handle, an application brush carried by the outer end of said extension, 25 a tank carried by the lower face of the extension adjacent the brush, a moistening roller mounted 25 in the tank and extending above the upper end thereof, a tension device above said moistening roller and comprising two spaced arms, whereby 30 a roll of tape may be mounted on the reel and passed over one arm and over the moistening roller and under the other arm of the tensioning device and under the application brush, and a tension device carried by the handle for the roll of tape. 35
